UNITED STATES PATENT OFFICE.

GEORGE A. LANGMAID, OF HAVERHILL, MASSACHUSETTS.

EYELET.

No. 826,672.

Specification of Letters Patent.

Patented July 24, 1906.

Application filed January 28, 1904. Serial No. 190,937.

To all whom it may concern:

Be it known that I, GEORGE A. LANGMAID, of Haverhill, in the county of Essex and State of Massachusetts, have invented certain new 5 and useful Improvements in Eyelets, of which the following is a specification.

This invention has relation to tubular eyelets, such as are employed in shoes and in garments of various kinds; and it has for its 10 object to provide certain improvements therein, to which reference will be subsequently made.

As hitherto constructed all metallic eyelets having the flange downwardly curved to 15 effect its engagement with the material have had a tendency to either cut into the material or else to permit the aperture formed in the material to be elongated when the material is under tension, particularly where the 20 eyelet is insufficiently clenched.

The object of the present invention is to provide an eyelet having its flange formed with a plurality of ribs or teeth formed on its under face for the purpose of rigidly engaging 25 without materially penetrating the fabric or material, and thus locking the eyelet, as it were, to the material. In thus constructing the eyelet the upper surface of the flange is substantially convex, with a flat 30 crimped outer edge which lies substantially flat upon the surface of the material, except for the indentations formed by the teeth, this said outer edge not only materially strengthening the eyelet, but also adding an 35 ornate or ornamental appearance thereto. The crimping of the flat edge is accomplished by dies and serves to materially harden the metal of the eyelet, as will be readily understood by those acquainted with this art.

40 Referring to the accompanying drawings, Figure 1 represents in side elevation an eyelet embodying the invention, the figure being drawn upon a relatively large scale. Fig. 2 represents a plan view of the eyelet. Fig. 3 45 represents the obverse or under side of the eyelet. Fig. 4 represents a section on the line 4 4 of Fig. 1. Fig. 5 represents a section through the eyelet when it is clenched upon the work, being, as it were, a section on the 50 line 5 5 of Fig. 2.

Referring to the drawings, the tubular body portion of the eyelet is indicated at 10, its lower end being inturned, as at 11, to enable said body to more easily enter the aperture formed in the material for its reception. 55 The upper end of the eyelet is bent over, as

at 12, to form the concavo-convex flange, the convex face of which is uppermost, as clearly illustrated in Fig. 4. The edge or rim of the flange is relatively flat and projects outwardly 60 in a plane substantially perpendicular to the axial center of the tubular body portion. By means of suitable dies or other mechanism the flat rim is formed with a plurality of teeth 14 14, which project downwardly from the 65 plane of the rim, these teeth being produced by corrugating the rim, so that the upper surface thereof has a series of radial convexities and depressions or grooves. This flat corrugated rim, as previously stated, greatly 70 strengthens the flange and provides a plurality of slightly-concave bearing-surfaces 13 with alternating teeth 14, so that when the eyelet is clenched upon the work, as shown in Fig. 5, the surfaces 13 bear upon the surface 75 of the material and the radial teeth 14 project downwardly into depressions in the material formed by said teeth.

When the eyelet is clenched upon the work or material, as shown in Fig. 5, the teeth 14 80 and intermediate portions 13 of the flange or rim bear upon the material so as to firmly grip the edges of the material around the hole through which the body portion 10 passes and prevent any pull on the material from 85 elongating the hole, so as to disengage its edge from the corrugations, and since there are no penetrating portions of the rim or flange that would have a tendency to cut the fibers of the material or work the connection 90 of the eyelet is more permanent than when a circular edge or pointed prongs are relied upon to grip the material.

It is to be distinctly understood that by the term "corrugated" I do not intend to include structures which have any sharp cutting or penetrating portions. 95

The eyelet as a whole may be japanned or otherwise finished, as requirements or fancy may dictate. 100

Having thus explained the nature of the invention and described a way of constructing and using the same, I declare that what I claim is—

1. An eyelet having a tubular body portion with an outturned flange at one end, 105 said flange having a crimped rim, the portions of the said rim which bear on the fabric to which the eyelet is connected being rounded to avoid cutting or penetrating the fabric. 110

2. An eyelet having a tubular body portion one end of which is curved outwardly

and downwardly to form a flange, said flange being formed with a crimped rim lying in a plane substantially perpendicular to the axial center of the tubular body portion, the under 5 surface of the crimped rim presenting a series of rounded ribs adapted to grip fabric without penetrating or cutting it.

In testimony whereof I have affixed my signature in presence of two witnesses.

GEORGE A. LANGMAID.
